ELEVATOR SYSTEM

Le Roy H. Kiesling, Brooklyn, N. Y.

Application November 10, 1942, Serial No. 465,111

18 Claims. (Cl. 187—31)

1

This invention is a novel elevator system, having reference particularly to a construction of gate for closing each gateway of the elevator, and to an arrangement for the control of the power drive of the elevator operated from a gate, and to a cooperative combination of such gate features and control features.

The improvements hereof is adapted to various practical uses, for example on passenger or freight elevators, or for dumbwaiters adapted to convey goods from floor to floor, under electric drive and push-button control. The elevator system may comprise one or a plurality of cars, each car traveling between two or more floors or stations within a hoistway, meaning any type of trunk or shaft; and the travel being either in a vertical manner, with a single car in the shaft, or on the other hand around an orbit, with a succession or train of cars moved step by step from station to station according to the control, exercised at will. Typical instances are for restaurant or factory use to shift provisions or goods from floor to floor, or for the elevating of supplies or munitions from a lower to an upper deck of a ship. In these various instances a gate is substantially essential in order to close the elevator gateway, at one or each side of the car, to confine safely and prevent falling out of goods therefrom.

The general objects of the present invention are to afford, in an elevator or dumbwaiter system of the kinds referred to, greater efficiency and convenience combined with safety. A further object is to provide a gate which is self-closing when released from the latch or other means employed to hold open the gate when the car remains stopped in the hoistway. Another object is to provide a simple and reliable control means for the electric or other drive, operable from the condition of the gate, whether open or closed, and which is sufficiently compact to be accommodated easily within the limited space usually presented in such installations. Further objects and advantages will be explained in the hereinafter following description of an illustrative embodiment of the invention or will be understood by those conversant with the subject. To the attainment of such objects and advantages the present invention consists in the novel elevator system including novel features of operation and control and features of collapsible gate, as well as novel features of combination, arrangement and construction herein illustrated or described.

In its preferred embodiment the invention, in a power-driven elevator system, comprises a car gate which is hung from the gateway lintel and

2

is collapsible upwardly for opening, and which undergoes lateral distension during upward collapse, in cooperation with a means or switch to control the power operation of the car, and a connection whereby the lateral distension of the gate during opening causes such control means to render inoperative the power drive. The lateral position of the gate is determinable, as by spring means located near the lintel.

- 10 In a particular aspect the invention may be outlined as consisting of a power-driven elevator system of the kind wherein the car, or each car in the hoistway, has a collapsible gate closing its gateway and wherein the control means comprises a movable contact arm or equivalent member mounted at a fixed position in the hoistway, for example protruding from a switch box, and cooperating therewith a shiftable actuator or cam mounted on the car and positioned to render the power drive inoperative when the gate is open and operative when the gate is shut, and such system being characterized by one or more of the following features. Regarding the collapsible gate, this is herein mounted at the top or lintel of the gateway, thus providing self-closing downwardly of the gate by gravity when released. Such collapsible gate is preferably of the type, which may be referred to as the lazy-tongs type, composed of crossed links between transverse bars, each link pair being centrally pivoted like a pair of scissors, and the link ends tending therefore to spread or separate transversely with the longitudinal collapse of the gate during opening, and vice versa, the link ends sliding along the transverse bars including the topmost or lintel bar as the bars relatively approach and separate in action. With such an elevator arrangement, a special feature hereof is that the shiftable actuator which swings the switch arm is shifted outwardly or inwardly on the car by a mechanical connection from one of the link ends, particularly a top end of a top link, so that during the opening or collapsing of the gate such link end, spreading outwardly, acts to thrust outwardly the actuator and thereby actuate the contact arm and control switch and prevent operation of car until the gate has been again closed.

In the accompanying drawings, Fig. 1 is a perspective view of an elevator or dumbwaiter car embodying the gate and control features of the present invention, with the gate shown in its lowered, expanded or closed position.

Fig. 2, on a larger scale, is a right elevation and part vertical section on the section line 2—2

of Fig. 1, showing the gate collapsed and open and latched so.

Fig. 3 is a rear elevation view showing the cooperation of the control means on the car and those in the shaft or hoistway, the wall of which appears in Fig. 3, the control switch box appearing in Figs. 1 and 3.

Fig. 4, on the same scale with Fig. 2, is a front elevation view partly broken away and partly shown in vertical section view.

Fig. 5, in perspective, and partly broken away, shows details of the collapsing gate bars and the latch means to hold open the gate.

Fig. 6 is a front elevation view, centrally broken away, showing particularly the construction of certain parts at the lower end of the car.

Fig. 7 is a left elevation and part section taken on the section line 7—7 of Fig. 6.

Referring in detail to the structure shown in the drawings, the hoistway or shaft wall 9 is not shown except partially by indication thereof in Fig. 3. The car 10 is shown in the form of a conventional dumbwaiter, but the illustration omits any showing of the hoisting means or cables or the power operating means or motors or the push buttons or similar manual controlling means at the respective floors or stations of the system. The car 10 may be described as comprising a ceiling or top wall 11 and a floor or bottom wall 12, near the edge of which is provided a cylindrical roll 13 to assist loading heavy goods; and right and left side walls 14, the car being shown open at both front and back sides, providing two gateways, the front one of which is shown as closable by a collapsible gate, while the other gateway might be similarly or otherwise closed.

Describing further the car construction, it is shown as having four corner uprights 16, and across the top front a lintel or fixed beam 17. These structural members and the walls may be suitably interconnected, as by welding. The corner uprights 16, especially at the two sides of the front gateway, are shown in the form of channel bars placed in facing opposition, so as to constitute upright tracks for the gate opening and closing movements. Also the lintel 17 may be hollow, constituting a barrel or guide for interior parts; for example, the lintel being shown composed of a pair of channels 18 facing each other and secured or welded at the tops of the corner uprights 16. Other conventional details of elevator car construction will be understood, without further reference.

Referring next to the operating control means there is shown at a fixed position in the hoistway, a control member in the form of a movable arm 20 which for example may be mounted swingingly upon an electric switch box 21 mounted on or in the hoistway wall and containing the switch devices and circuit connections necessary for operation, usually through relays, of the main or power switches by which the electric drive of the car is effected.

Cooperating with the arm 20, which is representative of any switch control member, is shown, mounted on the car, an actuator or retiring cam 22, this being shiftable, and with the arm 20 providing mechanical contacting means whereby the gate movements on the car are communicated to the controlling switch on the hoistway wall. Cam 22 acts as a shoe to thrust the arm.

While the shiftable mounting of the actuator or cam 22 may be varied, it is shown as mounted on a carrier shank 23, shown in the form of a bar or plunger and arranged to slide from an in-

ner or retired position to an outer or switch throwing position, for example within the groove or slideway provided between the facing channel bars 18 of the lintel or gateway top piece 17.

For certain reasons that will appear in describing the gate it is desirable that the actuator and its carrier or shank be spring-pressed outwardly, and for this purpose the shank or slider 23 is shown provided with an inward reduced extension 24 surrounded by a compressed helical spring 25, arranged within the guiding lintel and taking its seat upon the shank 23 and upon a central abutment or seat 27 which is preferably fixed. For purposes of symmetry, and for centralizing the collapsible gate, there is provided, at the other or righthand side of the abutment 27, a second compression spring 28 bearing upon a slider or shank 29. The symmetrically opposite sliders 23 and 29 are provided with depending ears or lugs 54 and 56, for the pivoted connection thereto of the topmost gate links, as will be further described.

Coming now to the collapsible gate 31, this is shown as hung from the lintel 17 so that its collapsing is upward, to open the gate, while when released it expands downwardly to close the gate. This is in distinction to the conventional arrangement of collapsible gates the longitudinal movements of which are horizontal, and which tend to remain in any position in which they are released. With the present invention the longitudinal movements of the gate are vertical, and being based upon the top piece of the gateway the strong expanding action of gravity affords reliably the self-closing action of the gate. The gate is shown collapsed or open in Figs. 2 and 4, where it is seen to be latched and held by a device 38 to be described. In this position the actuator 22 is held thrust outwardly and the power thus rendered inoperative while the car remains stopped and the gate open. Power operation can not be applied except after releasing and closing of the gate, which is readily effected by retracting the holding latch, the gravity self action thereupon reliably insuring the complete descent and closing of the gate; thus insuring safety against accidental or premature travel of the car.

The collapsible gate, shown of the preferable lazy-tongs type, may be described in detail as follows: It comprises a series of transverse or horizontal bars 32 and 33, which are guided in their up and down movements by the fixed channels 16, and which themselves form guides for the ends of the scissor-pivoted links 48. The top cross piece or lintel 17 may be considered the fixed top bar of the gate, and between this and the bottom bar 33 may be any number of other bars 32, of which four are shown, according to the desired height of car; and upon the bottom bar 33 is provided a convenient handle 34 by which the lifting or gate-opening movements may be manually brought about.

Like the fixed top gate bar, guide or lintel 17, each of the transverse bars 32 and 33 is shown consisting of a pair of mutually facing channels 35, thus providing guides or slideways for the ends of the crossed links. The spacing of the two channels for this purpose may readily be effected by the clamping of spacer blocks 36 between the channels at suitable points, for example near the ends and at the middle, one such block being shown in Figs. 4 and 5 near the left end of the bottom transverse gate bar 33. At this point may conveniently be described the releasable latch means to hold in its raised or upper position the

collapsible gate. For the purpose of such latching one of the spacing blocks 36 of the transverse bar 33 may be provided with a short downward extension to which is attached a horizontal extension or lug 37, projecting for example rearwardly, as seen in Figs. 4 and 5. Cooperating with this is a swingable latch 38, seen also in Figs. 1 and 2, of the duckbill type, so pivoted that its own weight tends to swing it into the latching position shown in Figs. 2 and 5. To apply the latch the gate is lifted by its handle 34 somewhat beyond its open position shown in Fig. 2, namely, to a tightly collapsed position as shown in Fig. 4, permitting the latch to swing in below the lug 37, so that when the gate is let slightly down the parts will take the position shown in Figs. 2 and 5, the weight of the gate holding the tail of the latch pressed against a fixed stop 39. To unlatch and release the gate for closing it is only necessary to lift slightly the handle 34, permitting the manual swinging away of the latch so that, upon letting go of the handle the gate will descend forcibly by its own gravity to the closed position of Fig. 1.

The several transverse bars 17, 32 and 33 of the car gate are caused always to remain parallel to each other, by the action of the crossed links connecting them, and for smooth action the ends of these bars, where they enter the upright channels 16 are provided with guide rollers 41, as best shown in Figs. 4, 6 and 7. It is frequently desirable to stop the closing movement of the gate at a point with the bottom bar 33 slightly above the car floor, as seen in Fig. 1, and in such case the bottom bar may be provided, at each end, with a drop extension or shoe 42, accommodated and sliding within the groove of the guiding channel 16. Near the lower end of the shoe 42 is shown an additional guide roller 41; so that the pair of guide rollers at each end of the bottom bar serves to afford a steady action and substantially prevent any tilting or inclining of the position of this bar. The bottom bar 33, and the top bar or lintel 17 thus remaining horizontal, all of the intermediate bars 32 efficiently maintain also a horizontal position whether or not the gate is in motion. As an additional expedient of advantage there is shown, below the lowest position of the gate, within each of the channels 16, a fixed block 44, these two blocks being secured to their channels and serving, as one purpose, to afford bearings for the cylindrical floor roll 13. As another function the blocks 44 carry rubber studs or bumpers 45, upstanding from the blocks and serving to receive the impact of the descending shoes 42 when the gate is closed.

The gate is composed of the described transverse bars, preferably horizontal, and a series of links 48, arranged in pairs between bars, each pair of links being symmetrically crossed and centrally pivoted to each other by a pin or rivet 49. Each of the links which is inclined downwardly toward the right in the closed gate position of Fig. 1 is arranged in front of the oppositely inclined link. This permits the two links of the pair above any given bar to be coordinated with the link-pair below the bar, without the need of bending or deforming any link to accommodate them smoothly to each other and to the bars whether the gate be open or closed. Thus the links of each pair are pivotally connected to those of the next pair above and below, namely by end pivots 50, which are accommodated inside of the channel groove of the intermediate bar. This construction is best shown

in Fig. 2 wherein each pivot pin 50 engages at its central portion the ends of the two meeting links 48; while, for smooth running qualities each such pivot pin carries at its respective ends small rollers 51, which may be fast or loose upon the pin, and which are confined within the opposite channels 35 of the transverse guide bar 32. Thus during the opening and closing movements of the collapsible gate, all of the movements of its constituent parts, the transverse bars and the crossed links, are under groove and roller guidance. As regards the connection between the lowest pair of links and the bottom bar 33, the fact that there is only one link end at each sliding pivot can be compensated by applying, upon the pivot 30 a small dummy piece or spacer, representing the absent link, and conveniently consisting of a washer or roller 52, as indicated in Fig. 2.

The top ends of the topmost link pair of the gate do not move freely, as do those running in the bars 32 or 33 therebelow, but are symmetrically constrained in their approaching and separating or spreading movements by the symmetrical springs 25 and 28 that are confined between the sliders 23 and 29 within the hollow lintel. Thus the topmost left link pivot pin 53 is shown as pivoted, not to another link, but to a depending lug or ear 54 of the slider 23; while similarly the top right pivot pin 55 is pivoted to the depending lug 56 of the slider 29. Consequently, as the gate descendingly closes the pivots 53, 55 are drawn horizontally toward each other, causing the sliders 23 and 29 to compress the two springs; and as these springs are preferably equal and are symmetrically centered by the abutment 27 the movement of approach of the two pivots, at the top ends of the topmost links, is a symmetrical action, the symmetry of which is carried down throughout the entire system of links from the top to the bottom of the gate.

In the arrangement thus described an advantageous action occurs. The springs may be under slight compression when the gate is open, as in Fig. 4, thus maintaining a tendency to move outwardly the sliders 23 and 29 and to thrust outwardly the actuator or shoe 22 toward the control arm 20 in the hoistway. When the gate is fully closed the springs 25 and 28 go under fairly high compression. They are selected however to provide, under these conditions, insufficient stress to overcome the weight of the gate, wherefore the gate may close itself by gravity, and when closed will remain closed. The springs however are at this time under considerable strain and therefore when manual opening of the gate is performed the springs, pressing apart the link ends spreadingly, afford substantial assistance, relieving greatly the manual work of lifting the gate to open position. In a sense the springs give partial counterbalance in easing the manual effort. As the rising gate however acquires increasing momentum the springs become more and more relaxed so that, due to this fact and to the change of angle of the links, the force of the springs becomes negligible. As the gate rises to its full open position self actuation will swing the latch 38 under the gate lug 37. In this position the spreading of the topmost link ends, by thrusting outwardly the slider 23 and shoe 22 will have rendered inoperative the power drive, this condition continuing until unlatching and dropping of the gate to closed position. During such gravity drop of the gate the springs again function advantageously, since their resistance to gate descent increases progressively, thus preventing

excess momentum and retarding the closing movement to a substantial extent, so that the gate comes to its full closed position without any undue shock or impact upon the bumpers 45.

The described spring mechanism is illustrative of a suitable resilient means tending to spread transversely the lazy-tongs side pivots or link ends, and thus tend to lift the gate toward open position, with preferably a symmetrical action.

There has thus been described an illustrative elevator system with car gate and power control features embodying the present invention; but since various matters of combination, arrangement and construction may be varied within the essence of the invention it is not intended to limit the same to such matters except so far as set forth in the appended claims.

What is claimed is:

1. A power-driven elevator system having a car in the hoistway with a longitudinally collapsible gate closing the car gateway, and having an operating control means comprising a movable control arm and cooperating therewith a shiftable actuator mounted on the car, said actuator having connections by which it may be positioned by the gate and adapted thereby to render the power drive inoperative when the gate is open and operative when the gate is shut; said system characterized in that the collapsible gate is mounted at the gateway lintel for downward self-closing by gravity expansion when released, and is composed of a pivoted series of pairs of crossed links between transverse bars whereby the link ends spread transversely apart with the longitudinal collapse of the gate during its opening, and vice versa; said actuator connections being operated by such transverse gate spreading action to cause a shifting of said actuator and thereby a control movement of said control arm to render inoperative the power drive.

2. A system as in claim 1 and wherein is a resilient spring means tending to open the closed gate and to shift the actuator to render inoperative the drive.

3. A system as in claim 1 and wherein is a resilient spring means tending to open the closed gate and to shift the actuator to render inoperative the drive, but insufficiently strong to overcome gravity and lift the gate without supplemental effort.

4. A system as in claim 1 and wherein is a resilient spring means tending to open the closed gate and to shift the actuator to render inoperative the drive; such resilient means comprising springs arranged to operate symmetrically, and the said actuator connections comprising sliders moved by the said springs and connected to the top ends of the top link pair.

5. A system as in claim 1 and wherein is a pivoted latch adapted by gravity to take a position to hold up the opened gate, but retractible to release the gate, and a stop to resist swing when the gate bears on the latch.

6. A system as in claim 1 and wherein the said actuator connections comprise a sliding shank at the lintel on which the actuator is mounted, the same being shiftable outwardly and inwardly, and said shank being connected to the gate linkage, whereby the link-end spreading action moves outwardly the shank and actuator as the gate opens.

7. A system as in claim 1 and wherein the said actuator connections comprise a sliding shank at the lintel on which the actuator is mounted, the same being shiftable outwardly and

inwardly, and said shank being connected to the gate linkage, whereby the link-end spreading action moves outwardly and shank and actuator as the gate opens; and wherein said sliding shank is spring-pressed outwardly and is directly pivoted to a link end.

8. A power-driven elevator system having a car in the hoistway with a longitudinally collapsible gate closing the car gateway, and having an operating control means comprising a movable control arm and cooperating therewith a shiftable actuator mounted on the car, said actuator having connections by which it may be positioned by the gate and being adapted thereby to render the power drive inoperative when the gate is open and operative when the gate is shut; said system characterized in that the collapsible gate is composed of a pivoted series of linkage members acting to spread transversely apart with the longitudinal collapse of the gate during its opening, and vice versa; and said actuator connections being operated by such transverse gate spreading action and adapted to cause a shifting of said actuator and thereby a control movement of said control arm to render inoperative the power drive.

9. A system as in claim 8 and wherein the said actuator connections comprise a slider shank mounted to move transversely out and in and carrying the actuator, and connecting means between the gate and shank, whereby the gate spreading action during opening moves outwardly the shank and actuator.

10. A system as in claim 8 and wherein the said actuator connections comprise a slider shank mounted to move transversely out and in and carrying the actuator, and connecting means between the gate and shank whereby the gate spreading action during opening moves outwardly the shank and actuator; said connecting means consisting of a direct pivoting of a gate link end to the shank.

11. A power-driven elevator having a car adapted to travel up and down in the hoistway, with a longitudinally collapsible gate closing the gateway, and having an operating control means; said system characterized in that the collapsible gate is a drop gate mounted at the gateway lintel for downward self-closing by gravity expansion when released, and is composed of a series of pairs of pivoted crossed links and transverse guide bars between which the link pairs are connected, whereby the link ends spread transversely with the upward collapse of the gate and vice versa; and in that at the lintel are opposite sliders spring-pressed transversely, to which sliders the top link-ends respectively are pivoted; whereby in the manual opening of the gate such springs assist the starting of the lifting movement, and in the gravity closing such springs retard the drop and reduce impact shock.

12. A power-driven elevator system having in the hoistway a traveling car with a longitudinally collapsible gate closing the car gateway, and having an operating control arm and cooperating therewith a shiftable actuator mounted on the car, said actuator having connections by which it may be positioned by the movements of the gate and adapted thereby to render the power drive inoperative when the gate is open and operative when the gate is shut; said system characterized in that the collapsible gate is of the linkage kind with a system of pivoted cross links and has its upper part mounted at the gateway lintel for downward self-closing by gravity expansion when released, said actuator connections being operated

by the lateral contraction of the linkage system during such gravity expanding action of the gate to cause shifting of said actuator in a manner to effect movement of said control arm to render operative the drive, and vice versa.

13. An elevator system as in claim 12 and wherein the car gate linkage spreads horizontally when collapsing vertically and vice versa, and is fitted for limited bodily shift along the lintel, and there is a resilient spring means acting horizontally upon the gate to determine yieldingly its position along the lintel and with tendency to spread the gate linkage and thereby to lift and open the gate but insufficient to lift it except with supplemental lifting effort applied at will.

14. A power-driven elevator having a car adapted to travel up and down in the hoistway, with a longitudinally collapsible gate of the linkage type closing the car gateway, and having an operating control means for the drive of the car; said system characterized in that the collapsible gate is mounted at the gateway lintel for downward self-closing by gravity expansion when released, accompanied by horizontal contraction in width of the linkage system, and vice versa, with means actuated by the width contraction and distension of the gate linkage system to operate said control means.

15. An elevator as in claim 14 and wherein the gate is fitted for bodily horizontal shift on the lintel, and there is a resilient spring means acting horizontally upon the linkage of the gate to position it horizontally and with tendency to distend the gate linkage and thereby to lift and open it but insufficient to lift it except with supplemental lifting effort applied at will.

16. In a power-driven elevator system with its car traveling in a hoistway, and on the car a gate of the lazy-tongs linkage kind comprising a system of crossed and mutually pivoted swinging links, said linkage gate being hung from the gateway lintel and collapsible upwardly for opening and expansible downwardly for closing the gate, and the linkage system of which undergoes horizontal distension during upward collapse and horizontal contraction during downward expansion, in combination with a control switch to con-

trol the power operation of the car and a control actuator therefor movably mounted on the car, and a connection from a horizontal end portion of the gate linkage system to said control actuator whereby the horizontal distension of the linkage system during gate opening causes movement of the control actuator and switch to render inoperative the power drive and vice versa.

17. An elevator system as in claim 16 and 10 wherein the mounting of the linkage gate upon the lintel is such that the gate linkage may shift bodily horizontally along the lintel, and wherein is spring means near the lintel and associated with the gate in a manner to determine yieldingly the position of the gate linkage along the lintel.

18. A power-driven elevator system having in the hoistway a traveling car with a longitudinally collapsible gate closing the car gateway, and having an operating control means comprising a movable contact arm and cooperating therewith a shiftable actuator mounted on the car, said actuator having connections by which it may be positioned by the gate and adapted thereby to render the power drive inoperative when the gate is open and operative when the gate is shut; said system characterized in that the collapsible gate is a drop gate mounted at the gateway lintel for downward self-closing by gravity expansion when released, and that such drop gate is composed of a series of pairs of pivoted crossed links and transverse guide bars between which the link pairs are connected, whereby the link ends spread transversely with the upward collapse of the gate and vice versa; and wherein the said actuator connections comprise at the lintel opposite sliders spring-pressed apart transversely, to which sliders the top link-ends respectively are pivoted; whereby in the manual opening of the gate such springs assist the starting of the lifting movement, and in the gravity closing such springs retard the drop and reduce impact shock; and the said actuator connections thus operated by such gate collapsing and expanding action being thus adapted to cause shifting of said actuator and thereby effect control movements of said contact arm.

LE ROY H. KIESLING.
